US00D558759S

(12) **United States Design Patent** (10) **Patent No.:** **US D558,759 S**
Tanaka (45) **Date of Patent:** **** Jan. 1, 2008**

(54) **COMBINED PERSONAL DIGITAL ASSISTANT AND AUDIO PLAYER**

JP D1225073 S 12/2004
JP D1236633 S 4/2005

(75) Inventor: **Soichi Tanaka**, Tokyo (JP)

(Continued)

(73) Assignee: **Sony Corporation**, Tokyo (JP)

Primary Examiner—Freda S. Nunn
(74) *Attorney, Agent, or Firm*—Rader, Fishman & Grauer PLLC

(**) Term: **14 Years**

(57) **CLAIM**

(21) Appl. No.: **29/274,652**

The ornamental design for a combined personal digital assistant and audio player, as shown and described.

(22) Filed: **May 14, 2007**

DESCRIPTION

Related U.S. Application Data

(63) Continuation of application No. 29/244,636, filed on Dec. 13, 2005.

(30) **Foreign Application Priority Data**

Sep. 9, 2005 (JP) D2005-026182

(51) **LOC (8) Cl.** **14-02**

FIG. 1 is a perspective view of a combined personal digital assistant and audio player showing my new design;

(52) **U.S. Cl.** **D14/341; D14/346**

FIG. 2 is a front elevational view thereof;

(58) **Field of Classification Search** D14/341-346,
D14/125-129, 371, 496, 358, 138, 156; 345/104,
345/156, 168, 173; 348/180, 184, 325, 373;
349/1, 2, 11, 62; 361/680-686; D21/329;
455/556.1, 90.3, 566, 575.3, 575.4

FIG. 3 is a left side elevational view thereof;

See application file for complete search history.

FIG. 4 is a right side elevational view thereof;

(56) **References Cited**

FIG. 5 is a top plan view thereof; and

U.S. PATENT DOCUMENTS

FIG. 6 is a bottom plan view thereof.

FIG. 10 is a left side elevational view thereof in the open position;

FIG. 11 is a right side elevational view thereof in the open position;

FIG. 12 is a top plan view thereof in the open position; and,

FIG. 13 is a bottom plan view thereof in the open position.

The even broken line showings in FIGS. 1-13 are for

illustrative purpose only and form no part of the claimed

design. The dot-dash broken lines in FIGS. 1, 2, 4, 7, 8, and

11 define, but are not included in, the boundaries of the

claimed design.
